UNITED STATES PATENT OFFICE.

ELIHU THOMSON, OF SWAMPSCOTT, MASSACHUSETTS, ASSIGNOR TO THE THOMSON-HOUSTON ELECTRIC COMPANY, OF CONNECTICUT.

METHOD OF CONSTRUCTING COMMUTATORS FOR DYNAMOS OR MOTORS.

SPECIFICATION forming part of Letters Patent No. 516,845, dated March 20, 1894.

Application filed January 24, 1891. Serial No. 378,891. (No model.)

To all whom it may concern:

Be it known that I, ELIHU THOMSON, a citizen of the United States, residing at Swampscott, in the county of Essex and State of Massachusetts, have invented a certain new and useful Improvement in Methods of Constructing Commutators for Dynamos or Motors, of which the following is a specification.

The present invention relates to a method of constructing commutators for electric motors, dynamos, or similar apparatus, and it consists in casting the metal parts of the commutator in a mold around or between the insulating division pieces or strips separating the segments. For this purpose a mold is prepared leaving a space or form in which the metal is to run when cast, and the division strips of insulating material are fixed in the mold in proper positions to form a commutator of the desired form and size when complete. I find that a suitable material for the division strips, and one which stands the heat of casting, is what may be called biscuit ware formed by baking clay at a moderate temperature, and producing a variety of earthenware material known as porous cup material or a material similar to porous cup material. It is a composition of clay tempered with a little sand and possibly a little feldspar. Other materials may suffice for the purpose of my invention, but this one I mention particularly as I have found it satisfactory.

My improved method will be understood by reference to the accompanying drawings, wherein—

Figure 1 is a section of a mold as prepared for casting; Fig. 2 a detail view of one of the division strips; Fig. 3 a view of the mold with division strips in place; Fig. 4 a perspective view of the casting; Figs. 5 and 6 are sectional and face views of the commutator mounted upon an armature shaft. Figs. 7 to 11 inclusive are corresponding views illustrating the method of casting a cylindrical commutator, and Figs. 12, 13, and 14 illustrate the same method, when the holders for joining the parts of the commutator together are fixed in the mold previous to casting rather than formed by the casting process itself.

In Fig. 1, C represents the upper part of a mold as prepared for casting consisting of

sand or loam rammed into the cope, and N is the lower half of the mold, between which is left the space K formed by a pattern, in which the metal is to run during the casting process. 55 The mode of procedure is more clearly shown in Fig. 3. Here the division pieces I, consisting of thin strips of biscuit ware or porous cup ware shaped as shown in Fig. 2, are placed in the mold with spaces between them for the 60 reception of the molten metal, which will preferably be of copper or copper slightly alloyed to assist its fluidity and soundness in casting. The division pieces are held in place by holders R, R' placed in the mold 65 which, as hereinafter described bind the parts of the commutator together, while it is being turned down or otherwise finished after casting. It is essential that the division pieces be firmly held, to resist the tendency to displacement when flooded with the molten metal. The holders R, R' are rings of metal, adapted 70 to receive and rigidly support the strips I. The segments, when cast, become welded to the holders, so that the product is a rigid article, which can be handled without danger of its falling apart. The gates used in the casting operation are seen at G, G. The holders may also be cast around the commutator, and for this purpose a space would be formed 75 in the mold as seen at l, Fig. 1. When the casting is taken from the mold it is as seen in Fig. 4, where G, G are the metal pieces formed by the gates or vents, K', K², K³, &c., are the metal segments of the commutator, I 80 the division strips, and R R' the holders or rings whereby the segments are not allowed to come apart or drop their insulating septums during the mechanical operations of finishing the commutator. The casting in Fig. 90 4 makes what may be called a disk commutator, that is, one in which the metal segments are in the form of a disk secured near its center. It is trued by putting it on an arbor and turning on a lathe in the usual way. When 95 finished, it may be mounted on the armature shaft, as in Fig. 5, where J is a sleeve over which the commutator is slipped, and J' a binding ring or follower secured by a clamping nut S. The parts J, J' fit into V-shaped 100 depressions in the commutator whereby the parts are held in place during revolution, and

a layer of insulating material, seen in black lines, is interposed to insulate the segments from the shaft. The holding ring R, which is cast solid without insulation will now be turned off or otherwise removed.

Where the commutator is of the cylindrical instead of disk variety, a pattern will be made as represented in Fig. 7, having thin projecting ridges P at positions corresponding to those in which the division strips are to occupy, and having also raised portions R¹, R², to form spaces in the mold for the ring holders which as before explained are to be cast solid around the commutator. The rest of the pattern takes approximately the form of the finished commutator. This pattern is set up in a mold rammed in the ordinary way, and when withdrawn leaves the mold as represented in Fig. 8, where the depressions P', P' formed by the ridges P, P, on the pattern are ready for the reception of the insulating strips which are set into the mold, as shown in Fig. 9, and the whole is ready for the pouring in of the metal. The casting produced will of course correspond in shape to the pattern in Fig. 7. It will then be turned and finished as before, and the rings will preferably be allowed to remain until the very last.

In Fig. 11 the commutator is shown complete and mounted on an armature shaft by taper sleeves, or in any other suitable manner which may be preferred by the constructor.

In Figs. 12 to 14 an arrangement is illustrated in which the annular holders are not cast on the commutator, but are placed in the mold with the insulation strips, and serve to hold the latter in place during the casting operation. Here a pattern is constructed as in Fig. 12, and rings of metal are set into it as at R, R', R². These rings form prints in the mold and the prints are afterward filled by metal rings prior to casting, as in Fig. 13. To assist in holding the insulating strips in place, the rings are slotted or otherwise shaped so as to receive and secure the strips. This avoids difficulty in setting the pieces of insulating material in place, and the copper rings do not injure the casting operation, but weld themselves in with the molten metal, and bind the same together. At the same time they have sufficient rigidity and heat resisting power to preserve the insulating material in place at the time of casting, if the operation is done properly. In Fig. 14 a casting thus produced is shown, and the subsequent processes of turning, fitting, &c., will be the same as illustrated in the preceding figures.

By my invention I avoid some of the many difficulties in commutator construction, which are largely occasioned by the requirement of a durable insulation between the segments. The ordinary way of constructing commutators is to make the segments separately and fit them together one by one with intervening insulation. This requires very careful workmanship, but by my invention this

labor is rendered unnecessary and the whole matter reduced to extreme simplicity. The fluid metal gives the form of the parts required with the insulation in place. Indeed I find in many cases there is a strong adhesion between the cast metal and the insulating strips. The strips must of course be selected of such a character that they will not crack or sliver by the heat of molding or when the hot metal strikes them.

The process to be successful requires a peculiar kaolin ware or biscuit ware, and the mold and the kaolin strips must be dry, to prevent filaments of copper from short-circuiting the segments. The addition to the kaolin clay of a little sand, feldspar, mica, or the like serves to produce a ware, when baked at a moderate temperature, which is not liable to crack under the heat of the molten metal.

The method is of course applicable to different forms and dispositions of the commutator portions of electric apparatus, and I do not limit myself therefore to those described which show the structure as employed with dynamos or motors.

What I claim as new, and desire to secure by Letters Patent, is—

1. The method of constructing commutators, which consists in arranging the insulating division strips in a mold with holders by which they are held mechanically in positions corresponding to the desired form of commutator, casting the metal of the commutator around or between said division strips, finishing the commutator and removing the holders before or after the remainder of the finishing process.

2. The method of constructing commutators, which consists in placing in a mold concentric metal rings or holders, arranging radial division strips of insulating material between said holders whereby they are rigidly held in position, casting the metal of the commutators between said division strips, and removing said holders during the finishing process, substantially as set forth.

3. The method of constructing commutators, which consists in casting copper or an alloy of copper around or between insulating division strips of earthenware material, as set forth.

4. A commutator consisting of cast metal segments, and earthenware insulation separating the segments.

5. A commutator consisting of cast metal segments separated by strips of porous kaolin ware, substantially as described.

6. A commutator consisting of cast metal segments separated by strips of biscuit ware composed of kaolin mixed with toughening materials, substantially as described.

In testimony whereof I have hereto set my hand this 20th day of January, 1891.

ELIHU THOMSON.
